ABSTRACT OF THE DISCLOSURE

Method of and apparatus for handling cartons of facial tissue prior to packaging the same in shipping containers therefor. Such handling involves transient storage of individual cartons in metal receptacles called tote boxes each of which is sufficiently large to hold a great number of cartons; and the apparatus employed in such handling includes a tote box loader operative to fill each such tote box with facial tissue cartons for storage thereof, and further includes a tote box unloader for subsequently removing facial tissue cartons from tote boxes preparatory to packaging the cartons in shipping containers therefor. Such transient storage of facial tissue cartons prior to packaging thereof enables cartons containing variously colored tissue to be accumulated so as to permit cartons respectively containing tissue of different color to be packaged in a single shipping container.

The method includes the step of group processing cartons of facial tissue so that a plurality of cartons are handled at a time; and in this respect, loading of a tote box with cartons comprises collecting the same group-by-group to form a layer thereof and then placing the collected cartons within a box layer-by-layer. Subsequently, the cartons are unloaded from the tote boxes layer-by-layer, and cartons of one color are assembled with cartons of different colors for eventual packaging as mixed lots in shipping containers therefor.

This invention relates to a method of and apparatus for packaging cartons of paper facial tissue in shipping containers or cases therefor; and, in greater particularity, the invention relates to group processing facial tissue cartons for transient storage thereof preparatory to packaging mixed-lot cases of colored facial tissue.

For many years paper facial tissue has been packaged in cartons for sale to the consumer through retail outlets; and until quite recently white has been the only color in which facial tissue was available. At present, however, tissue is being offered in several different colors; and although there has been consumer acceptance of all such colors, it has been found that the rate of purchase varies as between different colors. This variation in rate of purchase, or sale to the consumer, has been burdensome to many retail outlets in that such outlets tend to become overstocked in certain colors in those instances where cartons containing tissue of any one color are ordered in case lots.

To avoid this situation, retailers have adopted the practice of ordering cartons of facial tissue in mixed-lot cases comprising several different colors. For example, a case of tissue may consist of 36 (24 is another common number) individual cartons, and a typical order might be for 11 cartons of white tissue, 8 cartons of blue tissue, 7 of yellow, 6 of green, and 4 of pink. Thus, there is imposed upon the tissue manufacturer the requirement for packaging mixed-lot cases of tissue, thereby necessitating the

2

availability of tissue in each of the various colors before packaging thereof can begin.

Unless several facial tissue lines are to be operated concurrently—one for each of the various tissue colors desired (which in the usual case is not practicable), it is necessary to accumulate and store a substantial number of cartons of each color before cartons in all of the desired colors are available for packaging thereof to form mixed-lot cases. By way of indicating the magnitude of the accumulation facilities required, a particular facial tissue line may use supply or parent rolls of paper sufficiently large to provide a continuous run of several hours (e.g., six or more) before the rolls are depleted and require replacement. Evidently, because of the large number (e.g., 100 or more) of parent rolls that may supply tissue concurrently, it is economically infeasible to interrupt a run prior to depletion of the parent rolls to change the color of the tissue being processed, and clearly then this means that facilities for accumulating and storing the enormous total production of several runs must be provided before mixed-lot cases can be packaged.

The present invention is especially useful in processing cartons of facial tissue for transient storage thereof prior to such cartons being used in packaging mixed-lot cases, and in such transient storage, a great plurality of individual cartons are stored within large metal receptacles which are referred to herein as tote boxes. As respects this invention, an object thereof, among others, is to provide a method of and apparatus for group processing cartons of facial tissue and the like and for accumulating cartons group-by-group to form a layer thereof and for thereafter loading a tote box with cartons layer-by-layer. The invention further includes a method of and apparatus for unloading each such tote box layer-by-layer preparatory to packaging the cartons of facial tissue in a shipping container therefor. Additional objects and advantages of the invention, especially as concerns particular features and characteristics thereof, will become apparent as the specification develops.

An embodiment of the invention is illustrated in the accompanying drawings in which:

FIG. 1 is a block diagram illustrating an entire box facial tissue production system embodying the invention;

FIG. 2 is a diagrammatic perspective view of the tote box loader component of the tissue production system;

FIG. 3 is a broken, transverse sectional view of the tote box loader and by-pass section therefor taken along the plane 3—3 of FIG. 1;

FIG. 4 is a broken, longitudinal sectional view of the tote box loader taken along the plane 4—4 of FIG. 1;

FIG. 5 is an enlarged, longitudinal sectional view similar to that of FIG. 4 but being confined to the apparatus shown in the right hand portion thereof;

FIG. 6 is a vertical sectional view through the entrance end of the tote box loader taken along the line 6—6 of FIG. 3;

FIG. 7 is a vertical sectional view, oriented transversely through the tote box loader, taken along the line 7—7 of FIG. 4;

FIG. 8 is a horizontal sectional view of the discharge end portion of the tote box loader taken along the plane 8—8 of FIG. 5;

FIG. 9 is a vertical sectional view through the entrance end of the tote box loader taken along the line 9—9 of FIG. 3;

FIG. 10 is a broken end view of the apparatus illustrated in FIG. 9 as observed from the left hand side thereof;

FIG. 11 is a broken, vertical sectional view taken along the line 11—11 of FIG. 3;

FIG. 12 is an enlarged elevational view of the mechanism shown in FIG. 3 adjacent the right hand end portion of the infeed conveyor (immediately below the section line 11—11);

FIG. 13 is an end view looking from right to left of the mechanism illustrated in FIG. 12;

FIG. 14 is a vertical sectional view taken along the plane 14—14 of FIG. 13 and illustrating the abutment position of the stop structure;

FIG. 15 is a vertical sectional view substantially the same as that of FIG. 14 but illustrating the stop in the release position thereof;

FIG. 16 is a longitudinal sectional view taken along the plane 16—16 of FIG. 1 illustrating a tote box unloader in side elevation;

FIG. 17 is a broken, vertical sectional view taken along the line 17—17 of FIG. 16;

FIG. 18 is an enlarged vertical sectional view taken along the line 18—18 of FIG. 17;

FIG. 19 is an enlarged vertical sectional view taken along the line 19—19 of FIG. 17; and

FIG. 20 is a broken end view looking from left to right of the mechanism illustrated in FIG. 19.

GENERAL DESCRIPTION

An entire box facial tissue fabrication line is illustrated in FIG. 1, and referring thereto it will be noted that such line includes a back stand generally denoted with the numeral 20. The back stand 20 constitutes a plurality of individual parent rolls (not shown) of tissue totaling, in the usual instance, 102 separate rolls each providing a web which is slit longitudinally as it is withdrawn from the roll into two individual webs each of facial tissue width (usually about 8½ inches wide). The paper webs are withdrawn concurrently from the parent rolls, and as such individual webs are advanced, they are folded into the desired size and are stacked one upon another to form a longitudinally extending "log" 21 comprising 204 individual webs oriented in vertical juxtaposition.

The log 21 is advanced into a saw and cartoning machine 22 which severs the log transversely at spaced-apart locations therealong to section the same into facial tissue lengths, and then places each such section into a carton therefor which is thereafter closed and advanced along a conveyor 23. Accordingly, the conveyor 23 has disposed therealong a succession of individual cartons oriented in side-by-side juxtaposition, which cartons are denoted with the numeral 24.

As concerns the present invention, the back stand 20, cartoning machine 22 and each of the cartons of tissue may be completely conventional and, as is well known, each such carton as a typical example, will contain 200 double-ply tissues folded into a C-shaped or Z-shaped configuration.

Adjacent the end of the conveyor is a tote box loader 25 and also a by-pass conveyor section 26 which terminates at a diverter 27. Associated with the diverter 27 is a discharge conveyor 28 which empties into a case packer 29 operative to place a group of cartons 24 (usually totaling 36) into a shipping case. After the shipping case has been packed it can be placed upon a pallet in a palletizer 30. The case packer 29 and palletizer 30 may be conventional pieces of equipment as respects the present invention.

Whether the cartons 24 are advanced through the by-pass section 26 or are advanced into the tote box loader 25 is a matter of manual selection made by an operator controlling the entire fabrication line by means of a control console 31. When the selection is such that the cartons 24 are advanced into the loader 25, the cartons are collected into individual layers comprising a plurality of transversely extending and longitudinally extending rows, and the cartons are then displaced layer-by-layer into a tote box 32 which, in the specific structure being considered, is sufficiently large to receive therein 972 indi-

vidual cartons. After the tote box 32 has been loaded with cartons, it is advanced along a conveyor structure 33 to a pickup station 34 where it is grasped by a storage bank loader 35 selectively movable along an elongated track 36.

Disposed along the track 36 is a storage bank 37 adapted to accommodate, in the apparatus shown, cartons containing tissue of five separate colors. For this purpose, the storage bank 37 is divided into five sections of equal capacity, which equality of capacity is not essential, respectively denoted by brackets and designated by the legends Color A through Color E. Each such section comprises a plurality of vertically stacked tiers each of which includes a plurality of tandemly disposed tote-box-receiving compartments. The storage bank loader 35 is movable along the track 36 to the pickup station 34 where it grasps a loaded tote box 32, then carries such tote box to the appropriate color section of the storage bank 37, elevates the tote box to an appropriate tier and row thereof, and finally displaces the tote box into the forwardmost compartment of such row from which the box enters the particular compartment intended therefor.

Ultimately, the storage bank 37 will contain a relatively large number of cartons of variously colored tissue, and a large capacity for the storage bank is required because a period of several hours of operation follows each loading of the back stand 20 with parent rolls of any one color. By way of example: a loaded back stand may accommodate a continuous period of operation of about six to eight hours, and a production line cannot practically be changed over from the cartoning of one color to the cartoning of another until the back stand 20 is depleted. Therefore, the storage bank 37 must be able to accommodate an entire run of each of four colors (assuming a 5-color operation) before cartons containing the fifth color can be packaged and shipping cases packed with cartons of each color. By way of indicating the size of the storage bank 37, it may have a capacity of 640 tote boxes containing 622,080 cartons of facial tissue so that each such color section will have a capacity of 128 tote boxes.

The particular storage bank illustrated is comprised of three separate structural components denoted 37a, 37b and 37c, but the arrangement is a matter of choice.

The number of cartons of each color of tissue which will be packed in any one case is predetermined, and cartons in appropriate number and color in accordance with such determination are automatically delivered to the aforementioned discharge conveyor 28 by a color selector mechanism 38. The delivery of cartons to the selector 38 is effected by a plurality of infeed conveyors 39a-39e, respectively adapted to receive cartons containing the various tissue colors. The infeed conveyors 39a-39e receive cartons from a group of tote box unloaders 40a-40e respectively associated with the infeed conveyors 39a-39e. Loaded tote boxes are delivered to the unloaders 40 by the storage bank loader 35 which withdraws such tote boxes from the storage bank 37 on command from the control console 31.

After a tote box has been emptied by an unloader 40, the empty tote box is advanced along a return conveyor 41 to the tote box loader 25 where it is available for a subsequent loading cycle. In the case where a sufficient supply of empty tote boxes 32 is available for use at the tote box loader 25, additional empty tote boxes may be diverted onto the conveyor structure 33 for return to the pickup station 34 from which it is deposited by the storage bank loader 35 into the storage bank 37. Should a need arise at the tote box loader 25 for additional empty tote boxes, they may be withdrawn from the storage bank 37 and delivered to the return conveyor 41 via a conveyor section 42.

A continuous supply of cartons of variously colored tissue is delivered by the infeed conveyors 39 to the selector 38, and the selector is operative to select and segregate or separate from such supply the requisite number of cartons of each tissue color and to arrange the separated

cartons into two rows along a combining or assembly table 43 from which the cartons are advanced onto the discharge conveyor 28. As explained heretofore, the conveyor 28 advances such two rows of cartons into the case packer 29 which functions in a conventional manner to pack such cartons into a shipping case. Evidently, the diverter 27 must be conditioned selectively to receive cartons from the combining table 43 or from the by-pass section 26, since it is necessary that each of these two components deliver cartons to the discharge conveyor 28 through the diverter 27.

Summarizing the operation of the box facial tissue fabrication line illustrated in FIG. 1, tissue webs are withdrawn from the parent rolls thereof provided at the back stand 20, and after being folded and stacked one upon another define an elongated log which is severed transversely into sections of carton length, each of which sections is then packaged into a carton therefor. The filled cartons are advanced in side-by-side succession toward the tote box loader 25 which is operative to place a predetermined number of cartons in each tote box 32. The loaded tote boxes are advanced one-by-one to the pickup station 34 from which they are deposited by the storage bank loader 35 into the storage bank 37 in the color section thereof corresponding to the color of the tissue.

When cartons having all of the necessary tissue colors are available in the storage tank 37, the storage bank loader 35 withdraws tote boxes from the storage bank and deposits each box at the appropriate tote box unloader 40 which is operative to unload the tote box and deposit the cartons therefrom on the associated infeed conveyor 39. Thereafter the empty tote boxes are returned to the tote box loader 25 and the cartons of tissue are fed into the color selector 38 which selects and segregates the requisite number of cartons of each tissue color and combines the segregated cartons into two parallel rows, which rows are then advanced by the discharge conveyor 28 into the case packer 29. Should it be desired to bypass the tote box loader 25, storage bank 37, tote box unloaders 40 and selector 38, the cartons 24 leaving the cartoning machine 22 are directed into the by-pass section 26 which delivers such cartons directly to the discharge conveyor 28 through the diverter 27; and in this event, each case will contain cartons of one tissue color only.

TOTE BOX LOADER

In initiating discussion of the tote box loader 25 and by-pass conveyor section 26 therefor, reference will be made in particular to FIG. 2 which diagrammatically illustrates the various functions of the tote box loader. As shown in this figure and as described heretofore, cartons 24 of facial tissue are advanced in side-by-side juxtaposition along the carton infeed conveyor 23, and adjacent the terminal end of such infeed conveyor is a two-position stop mechanism generally denoted 44 which in the active abutment position thereof illustrated, is engaged by advancing cartons and thereby terminates further movement thereof along the conveyor. After a predetermined number of cartons 24 have accumulated along the conveyor 23 rearwardly of the stop mechanism 44, an interrupter mechanism 45 located intermediate the tote box loader 25 and by-pass conveyor section 26 moves into gripping engagement with one or more cartons 24 in alignment therewith to prevent further movement thereof along the conveyor 23 toward the stop mechanism 44. Thereafter, a row-displacing pusher mechanism 46 is actuated to engage the cartons 24 then positioned between the stop mechanism 44 and interrupter mechanism 45 (which group of cartons constitute a row 47 thereof totaling 14 in the diagrammatic illustration of FIG. 2) to displace such row from the conveyor 23 and onto a stationary platform 48.

Following such displacement of a row 47 of cartons onto the platform 48, the interrupter mechanism 45 is actuated to enable the conveyor 23 to further advance cartons 24 positioned therealong toward the stop mechanism 44 and into abutment therewith. Thereafter, the

interrupter mechanism 45 is again actuated to grip the cartons then in alignment therewith and the pusher mechanism 46 is again energized to displace a subsequent row 47 of cartons onto the platform 48. Evidently, such displacement of a subsequent row 47 will cause the prior row (or rows) then on the platform 48 to be pushed forwardly therealong, and in the illustration of FIGURE 2, six individual rows or groups 47 are located on the platform 48 and, for purposes of identification, are denoted with the numerals 47a through 47f. Such six rows or groups 47 supported upon the platform 48 together define a layer 49 of cartons, which layer in its entirety is advanced from the platform 48 and into a tote box 32 by operation of a layer-displacing conveyor mechanism 50.

In the tote box loader 25 diagrammatically shown in FIG. 2, the layer 49 comprises eighty-four individual cartons 24 (i.e., 14 times 6) arranged in the aforementioned transversely extending rows 47 each of which is defined by a group of fourteen cartons. Each tote box 32 is adapted to receive a plurality of layers 49, and the tote box 32 shown as in the process of being loaded, has four such layers supported upon the movable bottom 51 thereof—such individual layers being denoted with the numerals 49a through 49d. For convenience of description, the tote box presently being loaded in the illustration of FIG. 2 may be considered to be located at a loading station or loading position generally indicated at 52, and after such tote box has been completely loaded, it is advanced from the station 52 along the path depicted by the directional arrow included as part of the FIG. 2 illustration. Such advancement of a loaded tote box is effected by the conveyor 33 which at the same time advances another tote box 32 into the loading station 52. Thereafter, an additional tote box is advanced into place along the conveyor 33 beneath the platform 48 so as to be ready for advancement into the loading station 52 during the next cycle of operation.

As concerns the by-pass conveyor section 26, it is employed whenever it is desired to bypass the tote box loader 25 and deliver cartons of tissue directly to the case packer 29. In many respects the by-pass conveyor section is quite similar to the tote box loader 25, and it includes a two-position stop mechanism 53 (not shown in FIG. 2, but see FIG. 3) selectively movable into an active abutment position to perform with reference to the by-pass conveyor the same function as the stop mechanism 44 with reference to the tote box loader 25. Similarly, an interrupter mechanism 54 operates in a manner analogous to that of the interrupter mechanism 45 to terminate intermittently the advancement of cartons 24 along the infeed conveyor 23 when the by-pass section 26 is being used. In further similitude with the tote box loader 25, a row displacing pusher mechanism 55 is associated with the by-pass conveyor section 26, and the mechanism 55 is cyclically operable to displace successive rows or groups of cartons from intermediate the stop mechanism 53 and interrupter mechanism 54 onto the by-pass conveyor 26 which delivers the cartons row-by-row (not layer-by-layer) to the discharge conveyor 28.

The tote box conveyor 33 will now be described with particular reference being made to FIGS. 3, 4 and 5, and considering the same it is seen that the tote box conveyor 33 comprises a pair of endless chains 56 and 57 which are spaced apart transversely so as to engage a tote box 32 supported thereon along the outer edges thereof, as seen best in FIG. 3. The chain 56 is entrained about a pair of longitudinally spaced sprockets 58 and 59 and correspondingly, the chain 57 is entrained about spaced-apart sprockets one of which is illustrated in FIG. 3 and is denoted with the numeral 60. The sprockets 58 and 60 are mounted upon a common shaft 61 journaled adjacent its opposite ends in bearings 62 and 63 which are respectively supported by frame components 64 and 65 adapted to stand upon a suitable floor or other support surface. The upwardly extending frame components 64

and 65 are rigidified by one or more horizontally disposed frame elements 66 and, quite evidently, because of the relatively great weights of the tote boxes 32 and quantities of facial tissue cartons carried thereby, the frame components of the apparatus must be substantial and a considerable number both of vertically disposed and of horizontally oriented frame components will be employed in the overall frame structure. In that such frame structure and the components thereof may be essentially conventional in form and function, no specific description thereof will be made.

As shown best in FIG. 8, the sprocket 59 (and its counterpart, not shown) is mounted upon a drive shaft 61' journaled adjacent its opposite ends in bearings supported by frame components of the apparatus, one such bearing being illustrated in FIG. 8 and denoted 62'. The drive shaft 61' extends outwardly from the adjacent frame components and is equipped exteriorly thereof with a sprocket 67 chain driven from a motor or other prime mover indicated by the drive sprocket 67'.

Located along the conveyor chain 56 are a plurality of guides in the form of longitudinally spaced rollers 68 which perform two functions. First, the rollers 68 serve as stops to limit movement of each tote box 32 from the return conveyor 41 into position beneath the platform 48, and second, to guide each tote box 32 as it is moved by the tote box conveyor 33 from a position beneath the platform 48 into the loading station 52. In an analogous manner, a plurality of guides in the form of rollers 69 are located adjacent the drive shaft 61 so as to guide each tote box 32 as it is moved from the conveyor 41 and into position beneath the platform 48.

Certain associated sections of the return conveyor 41 (FIG. 1) and tote box conveyor 33 are in the form of transveyors which enable the direction of movement of the tote boxes 32 to be changed by 90° at certain locations along such conveyors. Transveyors of the type used herein are commercially available and are well known in the art and need not be described in detail. Accordingly, it will only be noted herein, as is illustrated in FIG. 3, that such conveyors necessarily have sections which are substantially normal to each other and that at each location of interconnection, one of the conveyor sections is vertically displaceable to make it dominant at certain times in control of the article moving therealong, and to make it passive at certain other times so that the co-active conveyor section then has control of such article. In this reference, the return conveyor 41 at its location of intersection with the tote box conveyor 33 is the vertically movable conveyor section and it comprises a plurality of narrow rollers 70 mounted upon elongated supports 71 which in turn are carried by the movable piston components of a plurality of spaced-apart piston-cylinder members 72 operative to displace the supports 71 and rollers 70 carried thereby between the upper and lower positions illustrated in FIG. 3 in which the rollers 70 are effective and ineffective, respectively, to control the direction of movement of each tote box supported thereabove.

The loading station 52 is defined in part by releasable stop structure operative to limit forward movement along the conveyor structure 33 of each tote box 32 and thereby positively locate each tote box within such loading station 52. The releasable stop structure is shown in FIGS. 5 and 8 and is denoted in its entirety with the numeral 73. The stop 73 includes a roller 74 rotatably carried adjacent one end of a generally T-shaped lever 75 pivotally mounted adjacent another end thereof by a pin 76. The pin is supported by a stationary frame component 77, and an adjustable stop screw 78 permits selection of the precise limit of angular movement of the lever 75 in a clockwise direction about the axis of the pin 76. The lever 75 is resiliently biased toward its limiting inward position in a clockwise direction (shown in full lines in FIG. 8) by a compression spring 79 which at one end bears

against the lever 75 and at its other end bears against a fixed frame component 80. The spring 79 is a helical structure located coaxially circumjacent a pin or plunger 81 which adjacent one end is pivotally supported by the frame component 80 and thereby accommodates pivotal displacement of the lever 75 while positively relating the spring 79 with respect thereto.

The T-shaped lever 75 is selectively displaceable in a counterclockwise direction about the axis of the pin 76 to withdraw the roller 74 from its inner position of abutment with a tote box 32 to an outer position remote therefrom, illustrated by broken lines in FIG. 8, by a motor means 82 in the form of piston-cylinder structure, the cylinder element of which is fixedly connected to the frame component 80 and the moveable piston element of which is connected to the T-shaped lever 75. Evidently, when the motor means 82 is energized, the piston and rod thereof are displaced in a direction causing counterclockwise movement of the lever 75 about the axis of the pivot pin 76 therefor to move the roller 74 into its retracted position against the biasing force of the spring 79.

Each tote box 32 is displaced along the return conveyor 41 and onto the conveyor 33 at a location beneath the platform 48 thereof by reciprocable displacement mechanism 83 comprising an elongated cylinder 84 fixedly supported by appropriate frame components of the tote box loader 25. The mechanism 83 further includes a reciprocable piston equipped with a rod or plunger 85 which has affixed thereto a finger 86 adapted to engage an edge portion of a tote box 32 and thereby enforce movement thereon when the piston rod is displaced toward its innermost position.

More particularly in this respect, when a tote box 32 is moved by the return conveyor 41 into a position of alignment with the platform 48 so that it may be displaced thereunder, as shown in FIGS. 2 and 7, the plunger 85 of the cylinder 84 is in the outermost position thereof shown by broken lines in FIG. 7, wherefore movement of a tote box 32 into such position of alignment orients the same for engagement by the finger 86. Thereafter, energization of the cylinder 84 to displace the rod or plunger 85 toward the right, as viewed in FIG. 7, causes the tote box 32 then in alignment with the finger 86 to be displaced along the return conveyor 41 and into position beneath the platform 48. It will be appreciated that during such displacement the aforementioned piston-cylinder members 72 will have been energized to elevate the rollers 70 of the return conveyor 41 into the uppermost position thereof in which the return conveyor controls movement of the tote box.

As explained hereinbefore, each tote box 32 is provided with a movable bottom 51 adapted to receive thereon a plurality of cartons 24. The purpose of such movable bottom 51 is to enable the tote box to be loaded layer-by-layer while maintaining the cartons 24 in a precise predetermined orientation relative to each other. In an analogous manner, the movable bottom 51 enables each tote box to be unloaded layer-by-layer without disturbing the predetermined orientation of the cartons 24. In this connection, the bottom 51 is shingled or has a stepped configuration which facilitates loading and unloading of the tote box by preventing misalignment or improper positioning of one or more cartons 24, which improper positioning might interfere with such layer-by-layer processing thereof. A complete and explicit explanation of such features and characteristics of the tote box are set forth in copending patent application Ser. No. 633,088 filed April 24, 1967, now Pat. No. 3,421,655, and insofar as such details may find application herein, they are incorporated by such reference to this copending patent application.

Referring to FIG. 5, it will be seen that the movable bottom 51 of the tote box 32 there illustrated is in an intermediate position and has four layers of cartons 24 supported thereon. Such four layers are respectively de-

noted with the numerals 49a, 49b, 49c and 49d, and each such layer comprises six transversely extending rows or groups 47 of cartons, the corresponding groups in such layers 49 being vertically juxtaposed in substantial alignment as evidenced by the numerically designated rows 49f respectively comprised by the layers 49a through 49d. Evidently, the movable bottom 51 is freely displaceable within the tote box 32, and the bottom in its lowermost position is supported perimetricaly by inwardly projecting support edges provided by the tote box. Displacement of the bottom 51 through various vertical locations above such lowermost position are enforced thereon by a jack assembly 87 which is illustrated most clearly in FIG. 5.

The jack 87 is essentially a scissors type jack having pivotally interconnected levers 88 and 89 each of which comprises two separate arms or branches in the particular structure shown. At its upper and lower ends, the lever 88 is pivotally connected, respectively, to a movable floor or platform 51a through a depending ear 90 and to the frame of the tote box loader through an upwardly extending ear 91. Although supported for pivotal movement adjacent its opposite ends, the lever 88 at such ends is fixed against translational displacements with respect both to the floor 51a and to the frame of the tote box loader.

The lever 89 at its upper end is pivotally connected to the floor or platform 51a through a slot-equipped depending bracket 92 which permits limited translational displacements of such end portion of the lever relative to the floor 51a within the limits defined by such slot. In a similar manner, the lower end of the lever 89 is pivotally connected to a frame component of the tote box loader through a slot-equipped guide or bracket 93 which permits limited translational displacement of such end portion of the lever relative to such frame. The translational displacements afforded for the end portions of the lever 89 evidently accommodate movement of the bottom 51 (i.e., floor or platform 51a which supports the bottom thereon) from the extreme lowermost position thereof (see FIG. 16), through the intermediate position shown in FIG. 5, and into an uppermost position, generally shown in FIG. 4, in which the upper surface thereof is located in substantial alignment with the platform 48.

Such movement of the floor or platform 51a is enforced thereon by a motor means 94 in the form of a fluid actuated piston-cylinder structure, the cylinder element of which is supported by a frame component of the tote box loader through a pivot pin 95 permitting angular displacement with respect thereto. The reciprocable piston of the motor means 94 is equipped with a rod or plunger 96 pivotally connected by a pin 97 to the upper branch or arm of the lever 89. Quite evidently, when the motor means 94 is energized to displace the piston rod 96 outwardly, the bottom 51 will be moved upwardly within the tote box 32, and reverse actuation of the motor means to displace the rod 96 inwardly will cause the bottom 51 to descend. As indicated hereinbefore, the movement of the bottom 51 is a step function related to the layer-by-layer loading and unloading of the tote box.

The infeed conveyor 23 will now be described with particular reference being made to FIGS. 2, 3, 6, 9, 10 and 12 through 15. The conveyor 23 includes an endless belt 98 entrained at opposite ends thereof about suitable drums, one of which is shown in the drawings (FIG. 3), and is denoted with the numeral 99. The drum 99 extends between and is rotatably supported by a pair of spaced-apart channels 100 and 101 fixedly supported by the frame of the apparatus. As shown in FIG. 3, the drum 99 is driven by a pulley or sprocket 102 having a belt or chain 103 drivingly engaging the same, which chain 103 is in turn driven by a suitable motor or other prime mover, not shown. As illustrated in FIG. 6, the endless belt 98 is located intermediate the ends of the drum 99 and is sufficiently narrow that a pair of stationary rails 104 and 105 respectively extend along the opposite longitudinal

edges of the belt and tend to support each carton 24 as it is advanced thereby.

The aforementioned stop mechanism 44 is disposed adjacent the outer terminal end of the infeed conveyor 23 and, as shown best in FIGS. 12 through 15, includes 5 an abutment plate 106 extending transversely of the infeed conveyor 23 and adapted to be engaged by the forwardmost carton 24 in a group or row thereof advancing along the conveyor. Accordingly, the abutment plate 106 defines the extreme limit of movement of cartons 24 along the conveyor 23 whenever the plate is in the carton-engaging position thereof. The abutment plate 106 is carried by a depending bar or bracket 107 which, at its upper end, is equipped with an annular hub or collar 108 supported 15 for pivotal movements about the axis of a pin 109 between the active position illustrated in FIG. 14 in which the abutment plate 106 is in the lower carton-engaging position thereof, and the retracted position illustrated in FIG. 15 in which the abutment plate 106 is in an elevated position in which it is ineffective to engage cartons 24 advancing along the conveyor 23.

The abutment plate 106, bracket 107 and hub 108 are resiliently biased for angular movement in a counter-clockwise direction, as viewed in FIG. 14, toward the retracted position of the abutment plate, shown in FIG. 15, 25 by a helical spring 110 which at its lower end is secured to an ear 111 affixed to the bracket 107 and at its upper end is anchored to a hanger 112 affixed to a stationary frame member 113. The abutment plate 106, bracket 30 107 and hub 108 are ordinarily retained in the carton-engaging position, shown in FIG. 14, against the biasing force of the spring 110 by a latch 114 pivotally supported intermediate the ends thereof and adapted at one end to engage the upper edge of the bracket 107. The latch 114 is resiliently biased into its bracket-engaging position, 35 illustrated in FIG. 14, by a helical spring 115 which at one end is connected to the latch and its upper end is affixed to the hanger 112.

The latch 114 is selectively movable into the release 40 position thereof, shown in FIG. 15, against the biasing force of the spring 115 by action of a solenoid 116 supported by the frame member 113 and having a movable plunger pivotally connected to the latch 114 through a 45 link 117. So long as the solenoid 116 is de-energized, the abutment plate 106 can be maintained in the carton-engaging position thereof, shown in FIG. 14, by the latch 114 through the biasing force imparted thereto by the spring 115. However, energization of the solenoid 116 elevates the latch 114 to release the bracket 107, whereupon it is swung upwardly as a consequence of the biasing force imparted thereto by the spring 110. Resetting 50 of the stop mechanism in the carton-engaging position thereof is a manual operation accomplished by simply swinging the abutment plate 106 and bracket 107 downwardly (an outwardly extending hand grip 118 being provided for this purpose) into the position shown in FIG. 14 whenever the solenoid 116 is de-energized.

It may be noted that in the usual case the abutment plate 106 is moved into the retracted position thereof, 55 shown in FIG. 15, only upon malfunctioning of the tote box loader 25, by-pass conveyor section 26, or equipment following thereafter so as to permit the back stand 20 and cartoning machine 22 to continue to operate by providing a path of discharge for the cartons emanating therefrom. A push-button limit switch 119 located so as to 60 be actuated by movement of the abutment plate 106 into the retracted position thereof (compare FIGS. 14 and 15) is included in the apparatus and it may be used in association with an indicia device to provide an indication of such positioning of the abutment plate in its elevated position.

Associated with the stop mechanism 44 is control apparatus which includes an actuator 120 carried by a hanger 121 supported by a collar 122 circumjacent the 65 aforementioned pin 109 for pivotal displacements with 70

respect thereto. Also carried by the collar 122 is a cam-type switch actuator 123 that is cooperatively engaged by the cam follower 124 of a switch arm 125 operative to control the condition of a limit switch 126. In this respect, the hanger 121 and actuator 120 are gravity biased into the downward position, shown by full lines in FIG. 12, in which a portion of the actuator 120 extends rearwardly of (to the left, as viewed in FIG. 12) the abutment plate 106 so as to be engaged by a carton moving theretoward slightly before such carton engages the abutment plate. Such condition of initial engagement of the actuator 120 by a carton 24 is illustrated in FIG. 12, and following such engagement, the actuator 120 is displaced in a counterclockwise direction, as viewed in this figure, about the axis of the pin 109. Such counterclockwise angular displacement results in the cam 123 displacing the arm 125 of the switch 126 to trip the same, thereby commencing a cycle of operation in which a group or row of cartons disposed along the conveyor 23 are displaced by the pusher mechanism 46 onto the platform 48.

As a part of such cycle of operation, the entire structural assemblage comprising the stop mechanism 44 is angularly displaced in a counterclockwise direction, as viewed in FIGS. 12 and 14, from the normal inner position thereof shown by broken lines in FIG. 14 into its outer position illustrated by full lines in such figures so as to relieve the row of cartons 24 in engagement with the abutment plate 106 from compression by allowing the row to move through a limited distance forwardly or toward the right along the conveyor 23, which displacement of the cartons and slight relief of compression facilitate displacement thereof from the conveyor 23 and onto the platform 48. Evidently, the structural assembly comprising the stop mechanism 44 is supported for such pivotal displacements by and with respect to the pin 109, and in its entirety it is biased in a counterclockwise direction by a helical spring 127 affixed at its upper end to a stationary bracket 128 and at its lower end to a bracket 129 forming a part of such mechanism 44. The extent of the angular displacement of the stop mechanism 44 in a counterclockwise direction is determined by an adjustable stop pin or screw 130.

The structural assemblage comprising the stop mechanism 44 is angularly displaced in a counterclockwise direction against the biasing force of the spring 127 to cause the abutment plate 106 to relieve a row of cartons of compression by action of a push rod 131 which at its lower end is pivotally connected to a crank arm 132 equipped at its inner end with a collar 133 supported by the pin 109 for pivotal displacements with respect thereto. Evidently, the stop mechanism 44 is carried by such collar 133 which then affords the aforementioned permissible pivotal displacements thereof relative to the pin 109.

As shown in FIG. 3, the push rod 131 at its upper end is pivotally connected to one arm of a bell crank 134 supported intermediate the ends thereof by a collar 135 for angular movement about a shaft 136. The other arm of such bell crank 134 is provided with a cam follower 137 that ridingly engages a cam 138 mounted upon a main drive shaft 139. Upon rotation of the shaft 139, the cam 138 is rotated and, as a consequence thereof, the push rod 131 is displaced upwardly to cause the crank arm 132, bracket 107 and abutment plate 106 to be rotated in a clockwise direction into the position shown by broken lines in FIGURE 14 against the resilient biasing force of the spring 127.

The row-displacing pusher mechanism 46 will now be described with particular reference being made to FIGS. 2, 3, 4 and 6. The mechanism 46 is cyclically operable to displace successive rows 47 of cartons from the endless belt 98 of the infeed conveyor 23 onto the stationary platform 48; and it includes an elongated pusher bar 140 that extends longitudinally along the conveyor 23 and is of sufficient length to engage each carton defining a

row 47 thereof so as to positively displace the same from the conveyor belt 98 and onto the platform 48. The pusher bar 140 is carried at spaced-apart locations therealong by a pair of arms 141 and 142 which are respectively connected to the bar through brackets or fasteners 143 and 144. Adjacent their upper ends, the arms 141 and 142 are clamped or otherwise secured to a shaft 145 which adjacent its opposite ends is journaled for rotation in bearing structures respectively provided by crank arms 146 and 147 clamped or otherwise fixedly secured to the aforementioned shaft 136 so as to be angularly displaced therewith.

The shaft 136 adjacent the crank arm 147 has a cam follower arm 148 secured thereto, which cam follower arm may be formed integrally with the crank arm 147 and defines a bell crank therewith. Adjacent its outer end, the arm 148 is equipped with a rotatable cam follower 149 adapted to ridingly engage a cam 150 configured so as to displace the cam follower 149 between the inner and outer positions thereof shown in FIG. 6, such outer position being depicted in phantom by broken line. The cam 150 is mounted upon the aforementioned main drive shaft 139 so as to rotate therewith.

The pusher mechanism 46 further includes a push rod 151 pivotally secured at one end thereof to the arm 141 and at its other to the lower end of a crank arm 152 which adjacent its upper end is clamped to a shaft 153 supported adjacent its opposite ends by frame components of the apparatus in suitable journals that permit angular displacements of the shaft. Intermediate its ends, the arm 152 is equipped with a rotatable cam follower 154 that ridingly engages a cam 155 configurated to displace the cam follower 154 between the inner and outer positions thereof depicted in FIG. 6. The cam 155 is mounted upon the aforementioned main drive shaft 139 so as to rotate therewith.

Evidently, rotation of the shaft 139 causes the cams 150 and 155 to rotate therewith, and rotation of the cam 155 results in the push rod 151 reciprocating the arms 141 and 142 and pusher bar 140 carried thereby from their outermost position, shown in full lines in FIG. 6, adjacent the outer lateral extremity of the infeed conveyor 23 to an inner position, indicated by broken lines in FIG. 6, in which the pusher bar 140 has been moved inwardly completely across the conveyor 23 to a position above the edge portion of the stationary platform 48. Continued rotation of the cam 155 returns the push bar 140 to its starting position. Thus, in one complete 360° rotation of the shaft 139 and cam 155 carried thereby, the pusher bar 140 is swung inwardly to displace a row 47 of cartons from the infeed conveyor 23 and onto the stationary platform 48 and is then returned to its starting position in preparation for another displacement cycle.

Concurrently therewith, simultaneous rotation of the cam 150 causes the entire pusher mechanism 46 to be displaced angularly with respect to the axis of the shaft 136 which causes the pusher bar 140 to traverse different, vertically-separated paths of travel as between the inward and outward displacements thereof. More particularly in this respect, just prior to the commencement of a cycle of operation, the pusher mechanism 46 is in the position thereof illustrated by full lines in FIG. 6, and upon initiation of such cycle, the pusher bar 140 begins to move inwardly toward engagement with the cartons defining a row 47 thereof along the infeed conveyor 23 because of the coaction of the cam 155, cam follower 154, and associated components as heretofore explained.

At the same time, coaction of the cam 150, cam follower 149, and associated components, as heretofore explained, causes the pusher bar 140 to move downwardly into the position denoted 140' in FIG. 6 at which position thereof the pusher bar is located at an elevation substantially along the center line of the cartons 24. The pusher bar is thereafter maintained at such eleva-

tion until it reaches its innermost position above the stationary platform 48, at which time the cam 150 causes the pusher bar to move upwardly to an elevation at which it clears any cartons 24 then disposed along the infeed conveyor to permit the pusher bar to be returned to the starting position thereof. Such arcuate path of travel traversed by the pusher bar enables the infeed conveyor 23 to commence advancing a subsequent row 47 of cartons toward the stop mechanism 44 without having to wait until the pusher bar 140 has been returned to its starting position, thereby increasing the productive capacity of the apparatus.

In order for the row-displacing pusher mechanism 46 to advance a row 47 of cartons from the conveyor 23 and onto the stationary platform 48, a minimum of interference should be presented by the successive cartons 24 being advanced along the infeed conveyor. Minimization of interference is provided in the present apparatus by interrupting advancement of cartons along the infeed conveyor during the brief interval that a row 47 of cartons is being displaced from the infeed conveyor. Such interruption is provided by the aforementioned interrupter mechanism 45 which will now be described in detail with particular reference being made to FIGS. 3, 6, 9 and 10.

The interrupter mechanism 45 comprises a pair of spaced-apart carton-gripper plate structures 156 and 157 each of which, as shown best in FIGURE 10, comprises a plurality of separate plate sections or segments, there being three in number in the structure shown and for purposes of identification such sections are respectively designated in FIG. 10 with the numerals 156a, 156b and 156c. The various sections comprising each of the plate structures 156 and 157 are resiliently supported by carrier plates 158 and 159 through a plurality of helical spring and plunger devices, collectively denoted with the numeral 160, operative to urge the plate structures 156 and 157 toward each other for engagement with any cartons 24 disposed therebetween, as shown in FIG. 6 (the number of cartons so engaged depending upon the length of the plate structures, and totalling three in the particular apparatus illustrated). As will be explained hereinafter, the springs impart a yieldable biasing force to the plate structures enabling them to grip tightly a carton 24 disposed therebetween without crushing or otherwise damaging such carton, which damage might result should the magnitude of the force imparted to the plates 156 and 157 through the carriers 158 and 159 be excessive.

The carrier plates 158 and 159 are selectively movable between an outer position illustrated in FIG. 9 in which the gripper plate structures 156 and 157 are remote from a carton 24 disposed therebetween, and an inner position shown in FIG. 6 in which such gripper plates are in engagement with a carton to prevent further movement thereof along the infeed conveyor 23. In order to accomplish such swinging movement of the carrier plates, they are respectively carried by depending arms 161 and 162 respectively supported by stub shafts 163 and 164 for pivotal displacements with respect thereto. The stub shafts are fixedly mounted upon one or more frame components of the apparatus, such as the transverse frame component 165 illustrated most clearly in FIGS. 6 and 9.

Respectively secured to the stub shafts 163 and 164 are a pair of crank arms 166 and 167 in a manner preventing relative rotation therebetween, and such crank arms extend inwardly from the shafts and adjacent their inner end portions are pivotally secured by a pin 168 to the bifurcated end portion 169 of a vertically oriented push rod 170. Adjacent its upper end, the push rod 170 is pivotally connected to one end of a crank arm 171 which at its opposite end is pivotally supported by the aforementioned shaft 136, and together with a depending arm section 172 (FIG. 3) forms a bell crank equipped

with a cam follower 173 that rides upon a cam 174 rotatably driven by the shaft 139. Evidently, rotation of such shaft 139 upon initiation of a cycle of operation causes the arm 171 and push rod 170 to be displaced upwardly with the result that the upward movement thereby enforced on the inner end portions of the arms 166 and 167 causes the carrier plates 158 and 159 to swing inwardly to bring the gripper plate structures 156 and 157 respectively carried thereby into carton-interrupting engagement with a carton 24 positioned therebetween.

Thereafter, as explained heretofore, inward movement of the pusher bar 140 is effective to displace a row 47 of cartons from the infeed conveyor 23 without excessive frictional interference from the next successive carton positioned along the infeed conveyor. As soon as the pusher bar 140 has cleared the infeed conveyor as it moves inwardly, the cam 174 will have been rotated into a position in which the push rod 170 will be moving downwardly to effect release of the carton 24 clamped between the plate structures 156 and 157, thereby enabling such carton and those following the same to be advanced by the conveyor 23. It will be apparent that the infeed conveyor 23 may run continuously, and the endless belt thereof simply slides beneath the cartons 24 constrained against movement therewith by action of the interrupter mechanism 45.

As shown best in FIG. 4, the cam follower 154 is resiliently maintained in engagement with the cam 155 associated therewith through a helical spring 175 which at one end is affixed to the frame of the apparatus and at its other end is affixed to an arm 176 that is clamped to the shaft 153, the spring thereby causing the arm 176 and shaft 153 to be biased in a clockwise direction, as viewed in FIGS. 4 and 6. In a similar manner, the cam follower 149 is urged into engagement with the cam 150 associated therewith by a helical spring 177 which at one end is affixed to the frame of the apparatus and at its other end is affixed to an arm 178 that is clamped to the shaft 136, the spring thereby biasing the arm 178 and shaft 136 in a counterclockwise direction, as viewed in FIGS. 4 and 6.

The main drive shaft 139 for the cams is driven through a drive train that includes a motor 179, gear reducer 180 to which it is connected by a drive belt 181 entrained about appropriate sheaves respectively carried by the motor and gear reducer, and a drive sprocket 182 mounted upon the shaft 139 and about which is entrained an endless chain 183 that is also entrained about a sprocket provided by the gear reducer 180. The motor 179 is operative to cycle the shaft 139 through one complete 360° rotation, and following any such complete revolution of the shaft, angular movement thereof terminates pending initiation of the next successive cycle of operation. Evidently, then, various control and limit switches are incorporated in the apparatus to effect such intermittently, cyclically repetitive operation of the shaft. In this reference, a one-revolution clutch can be employed as the connector between the motor 179 and gear reducer 180 in those instances where a continuously operative motor is used, although in other environments an intermittently operative motor may be employed.

As indicated hereinbefore, successive rows 47 of cartons are advanced one-by-one onto the stationary platform 48, and after a predetermined number of rows have been advanced thereonto, the entire layer 49 defined by such plurality of rows 47 is displaced in its entirety into a tote box 32 for support either directly by the movable bottom 51 thereof or indirectly thereby through a prior layer 49. The layer-displacing conveyor mechanism 50 by means of which such layer-by-layer loading of a tote box 32 is accomplished will now be described, and for this purpose reference will be made to FIGS. 1, 3 through 6 in particular.

The mechanism 50 includes a pair of endless chains 184 and 185 respectively entrained about sprockets 186, 187 and 188, 189. The chains 184 and 185 are driven

in enforced synchronism, and in this reference the sprockets 186 and 188 are mounted upon an idler shaft 190 located adjacent the infeed conveyor 23, and the sprockets 187 and 189 are mounted upon a drive shaft 191. The shaft 191 is driven through a drive train including a motor 192, gear reducer 193, and a drive chain 194 entrained at opposite ends about sprockets, one of which is connected with the gear reducer 193 and the other of which is mounted upon the shaft 191. The motor 192 is energized intermittently through control circuitry therefor including a switch 195 having a relatively long actuator arm 196 that extends over the stationary platform 48 and is adapted to be engaged and pushed upwardly by a carton 24 advanced therealong, as shown in FIG. 4. The actuator arm 196 is located with respect to the platform 48 so that the switch 195 is actuated whenever the final row 47 of cartons forming a layer 49 thereof is displaced onto the platform 48. Upon removal of such entire layer 49 from the platform 48, the actuator arm 196 returns downwardly to its lowermost position to signal the termination of a cycle of operation for the motor 192.

A layer 49 of cartons is removed from the platform 48 upon energization of the motor 192 by one or the other of a pair of conveyor flights or pushers 197 and 198 that extend transversely between the chains 184 and 185 and are fixedly secured thereto, as shown best in FIG. 6. The pusher flights 197 and 198 are equally spaced along the chains 184 and 185 and alternately engage the cartons defining the final row 47 forming successive layers 49 thereof. For the purpose of such engagement, each pusher flight has an L-shaped configuration and is adapted to engage the upper trailing corner portion of such final row 47, as shown in FIG. 4 by the pusher flight 198.

The conveyor mechanism 50 terminates its cycle of operation at about the relative disposition of the pusher flights 197 and 198 shown in FIG. 4, and in such position, the layer of cartons displaced by the conveyor mechanism during its cycle of operation from the platform 48 is located generally within the dimensional confines of a tote box 32 as such dimensions are projected upwardly from the upper edges of a tote box disposed in the loading station 52. As shown in FIG. 4, such displacement of a layer 49 into position above the tote box 32 causes a height-sensing switch 199 to be actuated because of the upward displacement of the actuator arm 200 thereof by engagement with cartons comprised in such layer 49. Actuation of the switch 199 causes the jack assembly 87 to index the bottom 51 of the box 32 downwardly one step.

Prior thereto, however, the direction of movement of the conveyor mechanism 50 is reversed and the conveyor travels reversely through a slight distance to withdraw the pusher 198 from the cartons displaced thereby, which reverse movement actuates a switch (not shown), and control circuitry associated therewith causes energization of a motor means 201 in the form of piston-cylinder structure, the cylinder of which is pivotally connected with frame components of the apparatus through mounting bracket structure generally denoted with the number 202. The reciprocable piston of such motor means is equipped with a rod 203 pivotally coupled to a confining or positioning displacer 204 in the form of an elongated plate that extends transversely with respect to the conveyor mechanism 50 and is adapted to engage each carton in the forwardmost row defining a layer thereof being advanced by the conveyor mechanism 50 into position above the tote box 32.

When the motor means 201 is energized, the rod 203 tends to be displaced toward the left, as viewed in FIG. 5, which causes the confining displacer 204 to be moved toward the left and into engagement with the cartons adjacent or immediately facing the same. Such engagement tends to move the row of cartons, and those rear-

wardly thereof, to the left to bring the lower trailing corner portion of each such carton into tight abutment with the upper forward corner portion of the carton therebelow (or step of the movable bottom 51 in the case of the first layer 49a). The purpose of such reverse displacement of a layer or cartons is to assure proper vertical disposition thereof with respect to the underlying rows of cartons.

At about the time that the confining displacer 204 has completed its reverse displacement of the layer of cartons, a vertically movable presser mechanism, generally denoted 205, is energized. Such mechanism 205 includes a plurality of depending presser feet 206 mounted upon carrier structure 207 supported for vertical displacements. Each of the presser feet extends transversely in the manner of the confining displacer 204, and such feet are respectively aligned with the various rows 47 of cartons supported by the movable bottom 51 of a tote box 32 located at the loading station 52. The carrier structure 207 is supported by a plurality of upwardly extending posts, there two shown in FIG. 5 which are respectively denoted with the numerals 208 and 209.

The posts are pivotally connected at their lower ends to the carrier structure 207, and at their upper ends the post 208 is pivotally connected to one free end of a bell crank 210 and, similarly, the post 209 is pivotally connected to one free end of a bell crank 211. The bell cranks 210 and 211 are respectively supported at the emergence of the legs thereof for angular displacements about shafts 212 and 213 fixedly related to frame structure of the apparatus. The other free ends of the bell cranks 210 and 211 are pivotally interconnected by a tie rod 214, which interconnection thereof causes such bell cranks to move in enforced synchronism. The shaft 213 is equipped with a crank arm 215 which is pivotally connected to a rod 216 operatively coupled with a motor means 217 in the form of piston-cylinder structure, the cylinder of which is pivotally anchored to frame structure of the apparatus and the piston of which is connected with the rod 216. One or more guides 218 confines the carrier structure 207 for vertical displacement.

Ordinarily the presser mechanism 205 is in the elevated position thereof shown in FIG. 5, but upon actuation of the switch 199, as heretofore described, the motor means 217 is energized, whereupon the rod 216 is moved inwardly, or generally toward the left as viewed in FIG. 5. As a consequence of such displacement of the rod 216, the shaft 213 is rotated in a counterclockwise direction with the result that the bell cranks 211 and 210 are similarly rotated, whereupon the carrier structure 207 is moved downwardly to bring the presser feet 206 into engagement with the cartons 24 in the underlying layer thereof to press the same downwardly into tight juxtaposition with the underlying layer of cartons 24 (or the movable bottom 51, as the case may be). Thus, the cooperative action of the confining displacer 204 and presser mechanism 205 assures a positive and proper location of each of the cartons 24 with respect to the tote box 32 and movable bottom 51 thereof.

The movable bottom 51 of the tote box 32 necessarily moves downwardly step-by-step as each successive layer 49 of cartons is advanced into position thereabove, and each step-by-step indexing of the movable bottom is initiated upon actuation of the aforementioned switch 199 through suitable control circuitry associated therewith and operative to energize the motor means 94 as a step function. Thus, as each layer 49 of cartons is advanced by the conveyor mechanism 50 from the stationary platform 48 and into position above the bottom 51 of a tote box 32 for receipt therein, the aforementioned mechanisms 204 and 205 positively locate the cartons of each such layer and the motor means 94 lowers the bottom 51 to condition the same for receipt of the next successive layer. As shown in FIG. 5, downward movement of each layer of cartons is facilitated by guides

219 and 220 respectively located adjacent the end of the conveyor 50 and adjacent the confining displacer 204.

As concerns control over a cycle of operation, a plurality of limit switches are used in this connection and are located along the shaft 139 for actuation by a plurality of cams carried thereby. However, since control circuitry of the type used in the present apparatus involving both limit switches and cam actuated switches is essentially standard, the complete circuitry is not treated herein because it is not essential to an understanding and complete disclosure of the present invention, and because inclusion of such circuitry would unduly burden the present description. For illustrative purposes, however, two such switches and the cam actuators therefor are illustrated in FIG. 11, and for identification, the switches are denoted with the numerals 221 and 222, and the cam actuators therefor are designated 223 and 224. Such cams, it may be noted, are mounted upon the main 139 so as to rotate therewith and, therefore, actuate the switches in a particular time relationship referenced to the rotation or angular displacement of the shaft 139.

As explained heretofore, the by-pass conveyor section 26 as it relates to the infeed conveyor 23 is substantially similar to the tote box loader 25. Accordingly, it may be said that the stop mechanism 53 associated with the by-pass conveyor section 26 is analogous in mechanism and function to the stop mechanism 44 heretofore described in detail. Therefore, details of the stop mechanism 53 will not be repeated herein since to do so would simply be a duplication of the disclosure presented with respect to the stop mechanism 44. As a convenience in establishing the visual correspondence of component parts as between the two stop mechanisms, the primed form of the same numerals used to identify certain of the components in the stop mechanism 44 are used in FIG. 3 to identify the respectively corresponding components of the stop mechanism 53.

The same comments are applicable with respect to the interrupter mechanism 54 and the row-displacer pusher mechanism 55 which respectively correspond structurally and functionally to the aforescribed interrupter mechanism 45 and row-displacer pusher mechanism 46 of the tote box loader 25. Accordingly, these mechanisms will not be again described and where appropriate, the primed form of the same numerals employed to identify component parts of the interrupter mechanism 45 and row-displacer pusher mechanism 46 are used in FIG. 3 to identify the respectively corresponding components of the interrupter mechanism 54 and row-displacer pusher mechanism 55. In the same sense other corresponding components are similarly designated including the motor 179', gear reducer 180', and shaft 139' driven thereby which respectively correspond to the motor 179, gear reducer 180, and shaft 139 heretofore described.

It will be apparent from the foregoing discussion that proper functioning of the tote box loader 25 and of the by-pass conveyor section 26 requires that the cartons 24 of tissue be properly oriented in a predetermined disposition as they are advanced along the infeed conveyor 23. That is to say, all of the cartons 24 are intended to have a contiguous juxtaposition in which each carton is resting upon a side wall thereof, and should a carton not have such orientation and, for example, be resting upon a top or bottom wall thereof (or in the unlikely event that it be resting upon an end), the apparatus could malfunction. To prevent this occurrence, a position-sensing mechanism is employed along the infeed conveyor 23 upstream of the by-pass conveyor section 26, and such mechanism is operative to detect the presence of and displace from the infeed conveyor any such misaligned carton.

In the present apparatus the position-sensing mechanism is electro-optical in character and includes a photosensitive cell, a light source and an ejector device responsive to a signal from such photosensitive cell to displace from

the conveyor a misaligned carton sensed by the photo-sensitive cell. Such apparatus is indicated in FIG. 3 and is denoted generally with the numeral 225. As concerns its position-sensing characteristics, the mechanism is conventional and includes a light source oriented along one side of the infeed conveyor 23 to project a light beam thereacross, and a photosensitive cell positioned along the opposite side of the conveyor to intercept the light beam. The photosensitive cell responds to any change in the condition of incidence of the light beam thereon to energize the ejector device and thereby displace from the infeed conveyor any carton causing such change in the incidence of the light beam. In that the structural composition of the mechanism 225 may be conventional, the foregoing description thereof is clearly adequate.

TOTE BOX UNLOADER

As illustrated in FIG. 1 and as described heretofore, a plurality of tote box unloaders 40 are included in the box facial tissue fabrication line (one for each color being processed), and each such unloader in a sense performs the reverse function of the tote box loader 25 in that it removes cartons 24 of tissue layer-by-layer from the tote boxes 32, which cartons were placed therein layer-by-layer by the tote box loader 25. A tote box unloader will now be described in detail with particular reference being made to FIGS. 16 through 20, and although the specific tote box unloader illustrated in these figures is the unloader 40e, numerical identification of the unloader and components thereof as illustrated in FIGS. 16 through 20 will be made without the inclusion of a letter suffix since all of the unloaders are essentially identical.

The unloader 40 includes frame structure generally denoted 226 that is provided along the bottom thereof with an infeed conveyor 227 adapted to receive thereon a tote box 32 delivered thereto by the storage bank loader and unloader structure 35. The conveyor 227 is operative to advance each tote box 32 from left to right, as viewed in FIGURE 16, wherefore each tote box passes under the color selector infeed conveyor 39 associated with such unloader. Each full tote box 32 resides temporarily at a ready station generally denoted 228 in FIGURE 16 until there is a requirement for such tote box at an adjacent unloading station 229. Such requirement occurs when a tote box 32 at the unloading station 229 has been completely unloaded and then removed from such station (displacement from left to right, as viewed in FIG. 16) either for return to the tote box loader 25 via the return conveyor 41 or for delivery to the pickup station 34, all as heretofore explained.

The tote box conveyor 227 for the unloader 40 is structurally similar to the tote box conveyor 33 for the loader 25 heretofore described, and includes a plurality of endless chains 230 adapted to support tote boxes thereon and entrained adjacent their opposite ends about sprockets at least one set of which is positively driven by motor means (not shown) upon command from appropriate signal devices. In view of the general similarity of the conveyor structures 33 and 227, and also because of the essential conventionality thereof, further details of the conveyor 227 will not be recited.

Included at the unloading station 229 is a jack assembly 231 which is substantially the same in terms of structure and function as the jack assembly 87 heretofore described in connection with the tote box loader 25. Accordingly, the jack 231 includes a scissors type lever system 232 operatively connected with a floor or platform 233 which seats thereon the movable bottom 51 of a tote box and is operative to index such bottom through a plurality of vertically spaced positions upon actuation of a piston-cylinder motor means 234. Since the jack assembly 231 is essentially the same as the jack assembly 87 described heretofore in detail, a part-by-part consideration of the jack assembly 231 appears

unnecessary and will not be set forth. It may be observed, however, that while the jack assembly 87 is operative to index the movable bottom 51 of a tote box 32 downwardly through a plurality of successive positions as the tote box is loaded layer-by-layer, the jack assembly 231 functions reversely to successively elevate the movable bottom 51 through a plurality of positions as the tote box is unloaded layer-by-layer.

Located above the unloading station 229 is a layer-displacing conveyor mechanism 235 which is analogous to the aforescribed layer-displacing conveyor mechanism 50 associated with the tote box loader 25. In this respect, then, the conveyor mechanism 235 includes a pair of transversely spaced endless chains 236 entrained at one of the ends about transversely spaced sprockets mounted upon a common shaft 237, and entrained at their opposite ends about transversely spaced sprockets mounted upon a common shaft 238. The shaft 238 is equipped with a drive sprocket 238 engaged by a chain 240 which is driven by a motor 241 via a drive sprocket 242 connected thereto. Extending transversely between the chains 236 at spaced-apart locations therealong are a pair of conveyor flights or pushers 243 and 244 adapted to selectively engage the successive uppermost layers of cartons as each such layer is indexed upwardly by the jack assembly 87 into proximity with the conveyor mechanism 235.

As concerns coaction of the pushers 243 and 244 with the successive uppermost layers of cartons provided by a tote box 32, it may be noted that the pushers are moved from right to left, as viewed in FIG. 16 (i.e., in a clockwise direction about the shaft 237), and such pushers in their path of travel alternately engage the successive uppermost layers of cartons. It should be observed that each tote box 32 is continuously maintained in precisely the same orientation as it moves through the entire fabrication and storage line shown in FIG. 1 so that, for example, the same side wall of a tote box will face toward the top of the FIG. 1 drawing as the tote box moves through the loader 25, along the conveyor structure 33, into the storage bank loader 35, into and out of the storage bank 37, through the appropriate unloader 40, and along the return conveyor 41 to the loader 25 to be used again in a subsequent cycle. Accordingly, the cartons 24 in any tote box 32 located at the unloading station 229 are stepped in a direction permitting the successive uppermost layers of cartons to be stripped from the underlying layer, or bottom 51 in the case of the final layer.

In being removed from a tote box 32, the cartons 24 have lateral confinement supplied thereto by transversely spaced guide members 245; and a guide member 246 is provided adjacent the forward or discharge edge of the tote box 32 to guide the cartons therat. All of the guide members 245 and 246 tend to maintain the cartons 24 in the layer-by-layer disposition thereof as the bottom 51 of the tote box is indexed upwardly by the jack assembly 231, and as each successive layer is displaced by the conveyor 235 onto a receiving conveyor 247 that overlies the ready station 228.

The receiving conveyor 247 comprises a plurality of relatively narrow, transversely-spaced belts 248 which are endless and at one of their ends are entrained about an elongated drive drum 249, and at their opposite ends are entrained about an idler drum 250. The endless belts 248 are continuously driven and movement is imparted thereto by the drive drum 249 which is driven by a belt 251 entrained about a sheave drivingly connected with the drum 249 via the shaft 252 therefor. The drive belt 251 passes over a plurality of idler pulleys, as shown in FIGS. 16 and 18, and is driven by a pulley wheel mounted upon a shaft 252 so as to rotate therewith.

The shaft 252 is journalled for rotation in suitable bearings mounted upon the frame structure 226 of the unloader 40, and the shaft 252 is rotatably driven by a motor 253 via a belt 254 which at one end is entrained about a drive pulley mounted upon the shaft 252, and

at its opposite end is entrained about a drive sprocket connected with the motor 253. The motor 253 may operate continuously, but usually operates intermittently upon demand from the color selector 38 (as explained in copending application Ser. No. 562,204 filed July 1, 1966, now Pat. No. 3,371,767, dated Mar. 5, 1968), and through its connection with the shaft 252 drives the drum 249 which in turn imparts motion to the conveyor belt 248 tending to move cartons 24 supported thereon from right to left, as viewed in FIG. 16. It may be noted that longitudinally extending guide members 255 are provided along the sides of the receiving conveyor 247 to confine the cartons within fixed transverse dimensions during such movement thereof by the conveyor 247.

Adjacent the discharge end of the receiving conveyor 247 is a row-delivery mechanism operative to deliver cartons row-by-row from the conveyor 247 to the color selector infeed conveyor 39. Such mechanism includes an elongated transversely extending support or carrier 256 mounted at its opposite ends on crank arms 257 and 258 respectively supported on stub shafts 259 and 260 for angular displacements therewith. As illustrated in FIG. 17, the shafts are journalled for rotation in bearings affixed to vertical components of the frame structure 226; and as shown in FIG. 18, the shaft 260 has secured thereto a crank arm 261 equipped at its upper end with a cam follower 262 adapted to ridingly engage a cam 263 effective to displace the follower 262 between an inner position, shown by full lines in FIG. 18, and an outer position, illustrated by broken lines. The cam follower 262 is resiliently biased into engagement with the cam 263 by a helical spring 264. The cam 263 is mounted upon the aforementioned shaft 252 so as to rotate continuously therewith.

The support 256, as best evidenced in FIG. 18, carries a relatively large, flat plate 265 that is movable with the support between a substantially horizontal position shown by full lines in such figure, in which position the plate is in substantial alignment with the belts 248 of the receiving conveyor 247 so as to receive cartons 24 therefrom, and an inclined position shown by broken lines in which it has been angularly displaced with respect to the axis of the stub shaft 260 and forms a stop preventing movement of cartons 24 thereonto. These two positions of the plate 265 respectively correspond to the inner and outer positions of the cam follower 262.

As concerns the stop-forming function of the plate 265, when it is displaced in a counterclockwise direction, as viewed in FIG. 18, by coaction of the cam follower 262 and cam 263, the inner end of the plate is swung upwardly into the path of movement of the next successive row of cartons 24 being advanced by the receiving conveyor 247, as shown in FIG. 18. Thus, such next successive row of cartons cannot be advanced onto the plate 265 until the plate has been returned to its horizontal position. However, such upward displacement of the plate 265 causes the row of cartons 24 then positioned thereon to be elevated into a position in which the pusher bar or flight 266 of a stripping conveyor 267 can engage the upper corner portion of each such carton to push the same from right to left, as viewed in FIG. 18, downwardly along the plate 265 and onto the color selector infeed conveyor 39.

The pusher bar 266 extends between a pair of transversely spaced endless chains 268 entrained at opposite ends about spaced-apart sprockets therefor which are mounted, respectively, on shafts 269 and 270. The shaft 270 is equipped with a drive sprocket operatively connected with a drive chain 271 driven by a sprocket 272 mounted upon the aforementioned shaft 252. Evidently, then, the chains 268 of the conveyor 267 are continuously driven because of their connection with the continuously (or intermittently) driven shaft 252, wherefore the pusher bar 266 traverses the path of travel defined by the chains

268. In traversing this path, the pusher bar engages any cartons 24 supported by the plate 265 whenever such plate is in its elevated position, and quite apparently the pusher bar 266, plate 265, and support 256 are synchronously related in a time sense since they are driven from the shaft 252. In that the conveyor 247 operates continuously, or intermittently upon demand as explained with reference to the motor 253 and conveyor belt 248 driven thereby, it is always conditioned to supply a row of cartons 24 to the plate 265 so long as any cartons 24 are positioned on the conveyor.

Also comprising a part of the tote box unloader 40 is an alignment-enforcing mechanism 273 illustrated in FIGS. 19 and 20 and operative to maintain each row of cartons 24 in aligned juxtaposition as it is displaced onto the color selector infeed conveyor 39 from the plate 265 by the stripping conveyor 267. More particularly in this respect, the color selector infeed conveyor 39 operates to provide at the color selector 38 a supply of cartons 24 of the particular color being handled by such conveyor. Evidently, then, since the conveyor 39 may be in motion at any particular time, cartons being discharged downwardly along the inclined plate 265 may touch a moving conveyor in which event they tend to be immediately advanced thereby. In that only the forward lower corner portion of each carton would be in initial contact with such moving conveyor 39, a skewed disposition would tend to be enforced on those cartons as a consequence of the relative movement between the traveling conveyor 39 and stationary plate 265. The alignment-enforcing mechanism 273 prevents such skewing of the cartons from occurring by constraining the entire row of cartons against movement along with the conveyor 39 until all of the cartons in their entirety are resting thereon.

The mechanism 273 includes an alignment or abutment plate 274 bolted or otherwise secured to a depending bracket 275 which at its upper end is bolted to a generally U-shaped pivot 276 supported for pivotal movement by a stationary carrier 277. Connected to the pivot 276 so as to enforce angular displacements thereon is a crank arm 278 pivotally connected to the lower end of a push rod 279 that at its upper end is pivotally connected to one end of an elongated lever 280. The lever 280 at its opposite end is equipped with a collar or hub 281 pivotally supported on a pin 282 mounted upon frame components of the apparatus, as shown at 283.

Formed integrally with or otherwise secured to the hub 281 is a cam follower arm 284 which at its outer free end is equipped with a cam follower 285 that rigidly engages a cam 286 operative to displace the cam follower 285 between the inner and outer positions thereof respectively illustrated in FIG. 19 by full and broken lines. The arm 284 is resiliently biased by a helical spring 287 in a clockwise direction, as viewed in FIG. 19, to maintain the cam follower 285 in engagement with the surface of the cam 286. The spring 287 is affixed at one end to the arm 284 and at its opposite end to stationary components of the apparatus.

The cam 286 through the cooperative interrelation of the cam follower 285, arm 284, lever 280, push rod 279, and crank arm 278 is effective to displace the alignment plate 274 between its lower carton-engaging position shown by full lines in FIG. 20 and its upper carton release position shown in FIG. 17. The cam 286 is mounted upon the shaft 252 so as to rotate therewith and, therefore, is driven continuously in enforced synchronism with the stripping conveyor 267 and with the angular displacements of the plate 265. Accordingly, movement of the alignment plate 274 between the two alternate positions thereof is timed with the conveyor and plate, and it may be noted that because of the differential between the lengths of the crank arm 278 and lever 280, angular displacements of the plate 274 between the alternate positions thereof will be quite rapid.

OPERATIONAL CYCLE

Considering an overall cycle of operation, cartons of facial tissue are advanced along the infeed conveyor 23 in contiguous juxtaposition and are intended to have a predetermined orientation since the three dimensions of a rectangular carton of facial tissue usually differ from each other. In the particular apparatus being discussed, the cartons 24 are intended to be supported upon a side wall thereof and to extend transversely of the conveyor so that the two ends of each carton are disposed adjacent the lateral edges of the conveyor. In the event that any particular carton 24 is improperly positioned as it is advanced along the infeed conveyor 23, the position-sensor mechanism 225 (FIG. 3) is operative to detect such condition of misalignment and to eject or displace the misaligned carton from the conveyor by imparting a transverse impulse or push to such carton to force it off of the conveyor.

In the usual condition of the apparatus, the by-pass conveyor section 26 is ineffective to control the processing of cartons 24 and, accordingly, the stop mechanism 53 (FIG. 3) is in the upper position thereof in which it does not interfere with the movement of cartons along the conveyor, and the interrupter mechanism 54 and row-displacing pusher mechanism 55 are maintained in the inactive positions thereof in which cartons are free to move without interference therefrom along the infeed conveyor. Thus, as the cartons move in side-by-side juxtaposition past the by-pass conveyor section 26, they eventually have their motion stopped by abutment of the leading carton of each successive group thereof with the abutment plate 106 of the stop mechanism 44 (FIGS. 3 and 12 through 15). Just prior to such engagement of each leading carton 24 with the abutment plate 106, such carton 24 engages the actuator 120 and displaces the same, which displacement thereof results in actuation of the switch 126, whereupon a cycle of operation is initiated.

As part of such cycle of operation, the shaft 139 begins to rotate, and the consequent rotation of the cam 138 mounted thereon causes the push rod 131 to displace the entire stop mechanism 44 in a counterclockwise direction, as viewed in FIG. 14, to relieve compression of the cartons 24, defining a row thereof, thereby facilitating movement of such row from the infeed conveyor and onto the stationary platform 48 of the tote box loader 25. Also as a part of such cycle of operation, the cam 174 is rotated by the shaft 139 whereupon the push rod 170 of the interrupter mechanism 45 (FIGS. 3, 6, 9 and 10) is caused to manipulate the carton-gripper plate structures 156 and 157 to effect inward displacement thereof from their outer positions shown in FIG. 9 to their inner positions shown in FIG. 6 to resiliently clamp a carton 24 therebetween. Such clamped carton 24 is thereby held against movement in either direction along the infeed conveyor 23 and, therefore, allows decompression of the row of cartons forwardly thereof upon the aforementioned angular displacement of the stop mechanism 44.

Also as a part of such cycle of operation, the shaft 139 rotates the cams 150 and 155 to bring the row-displacing pusher mechanism 46 (FIGS. 3 and 6) into action. Such action thereof causes the pusher bar 140 to traverse the arcuate path of travel depicted in FIG. 6 to advance the entire row or group of cartons defined between the stop mechanism 44 and interrupter mechanism 45 onto the stationary platform 48 of the tote box loader 25. As explained heretofore, as soon as such row of cartons has been displaced from the infeed conveyor, the interrupter mechanism 45 is released to enable the infeed conveyor to advance the next row-forming group of cartons into position between the stop mechanism and interrupter mechanism while the row-displacing pusher mechanism 46 is being returned to its starting position. The cyclic operation described continues repetitively so long as car-

tons are being advanced along the infeed conveyor 23, and each cycle is initiated by abutment of the leading carton 24 in a row thereof with the actuator 120 of the stop mechanism 44 because of the consequent actuation of the cycle-initiating switch 126.

Successive rows 47 or cartons continue to be advanced onto the stationary platform 48 until a predetermined number of rows are accumulated thereon, which accumulation thereof initiates operation of the layer-displacing conveyor mechanism 50 (FIGS. 4 and 5) as a result of the actuation of the switch 195 which follows engagement of the depending arm 196 thereof with a carton 24 moving into a predetermined position on the platform 48. Energization of the conveyor mechanism 50 selectively brings one or the other of the conveyor flights or pushers 197 and 198 into engagement with the upper trailing corner portion of the cartons defining the final row 47 thereof, and such pusher then displaces the entire layer 49 of cartons onto the movable bottom 51 (or onto a layer of cartons already supported by such bottom) of a tote box 32 located at the loading station 52. Such layer-by-layer loading of the tote box 32 continues until the tote box is entirely loaded in which condition thereof the movable bottom 51 is in its lowermost position within the tote box and is supported upon the inwardly turned bottom edges thereof.

Further concerning such layer-by-layer loading of each tote box, as soon as an empty tote box is moved into the loading station 52, the motor means 94 is energized through appropriate switch controls to displace the movable bottom 51 of such tote box upwardly and into a position of substantial alignment with the platform 48 (as shown in FIG. 4) so that the first complete layer 49 of cartons on such platform 48 can be displaced therefrom onto the bottom 51. The motor means 94 is then energized through switch control circuitry to displace the bottom 51 downwardly to the next successive position thereof in which the upper surfaces of the cartons 24 supported upon such bottom are then in approximate alignment with the platform 48 so that the next successive layer 49 of cartons can be displaced therefrom and onto the layer previously received by the bottom 51. The movable bottom 51 is then displaced downwardly through actuation of the motor means 94 to the next successive step for receipt of a subsequent layer 49 of cartons from the platform 48, and such step-by-step downward indexing of the bottom 51 continues seriatim until the tote box is completely loaded, whereupon the releasable stop structure 73 (FIG. 8) is retracted and the tote box conveyor structure 33 energized to remove such loaded tote box 32 from the loading station 52.

As explained heretofore, each successive layer 49 of cartons after displacement thereof onto the movable bottom 51 of the tote box, or onto a layer of cartons already supported thereby, is accurately located and positioned by the confining displacer 204 and by the presser mechanism 205. As concerns the confining displacer 204, the layer-displacing conveyor mechanism 50 may be thought of as imparting a slight over-travel to each layer 49 of cartons displaced thereby so as to make sure that the cartons of each such layer clear or pass over the upper forward corner portion of each carton therebelow, or the upper corner portion of the steps of the movable bottom 51, as the case may be. The confining displacer 204 compensates such over-travel by displacing the entire layer of cartons in the opposite direction to move the lower trailing corner portion of the cartons in each such layer toward the upper leading corner portion of the underlying cartons or stop.

The removal of a filled tote box 32 from the loading station 52 signals the requirement for an empty tote box thereat, and the tote box conveyor structure 33 then becomes operative to advance a tote box from the awaiting station therefor beneath the stationary platform 48 into the load-

ing station 52 concurrently with removal of a loaded tote box therefrom. Such concurrent advancement of an empty tote box from the awaiting station empties the same to condition it for receipt of another empty tote box advanced thereinto by operation of the reciprocable displacement mechanism 83 (FIGURE 7) which is made active by control switches actuated upon removal of a tote box from the awaiting station. Such operation of the displacement mechanism 83 is accompanied by energization of the motor means 72 to elevate the transveyor section supported thereon and thereby permit movement of a tote box 32 by the displacement mechanism 83 into the awaiting station. Upon return of the displacement mechanism 83 to the starting position shown by broken lines in FIG. 7, the motor means 72 lowers such transveyor section, whereupon the next successive tote box 32 located along the return conveyor 41 can be advanced into position on the transveyor section enabling the displacement mechanism 83 to advance the same into the awaiting station in the following cycle of operation.

After a filled tote box 32 leaves the tote box loader 25, it is advanced to the pickup station 34 whereat the storage bank loader 35 transports such tote box into an approximate storage location therefor in the storage bank 37. Whenever there is a need for tissue of the particular color stored within such tote box, the loader 35 removes the tote box from the storage bank 37 and deposits the tote box at the appropriate tote box unloader 40 for unloading thereat. After such tote box is so deposited at the unloader therefor, it is advanced into the ready station 228 along the infeed conveyor 227 (FIG. 16) of the tote box unloader. Each such tote box is subsequently advanced from the ready station 228 and into the unloading station 229 whereat the cartons 24 are removed therefrom layer-by-layer.

In this respect, movement of a tote box into the unloading station 229 energizes the jack assembly 231 to cause the motor means 234 thereof to elevate the movable bottom 151 of the tote box and cartons supported thereby into the first unloading position thereof in which the uppermost layer of cartons is adapted to be selectively engaged by one or the other of the conveyor flights or pushers 243 and 244 provided by the layer displacing conveyor mechanism 235 to remove such uppermost layer from the underlying support therefor and onto the receiving conveyor 247. This step-by-step elevation of the movable bottom 51 and removal of the successive uppermost layers of cartons is repeated seriatim until the tote box is completely unloaded at which time the motor means 234 of the jack assembly 231 returns the bottom 51 to its lowermost position and withdraws therefrom to enable the emptied tote box to be forwarded by the return conveyor 41 toward the tote box loader 25. The upward step-by-step indexing of the movable bottom 51 of each tote box when in the unloading station 229 is controlled by switch means appropriately located to sense the requirement for the next successive layer of cartons at a position in which the conveyor mechanism 235 can engage the same. Evidently, such switch means governs energization of the conveyor mechanism 235, which conveyor operates intermittently in accordance with the presence of a layer of cartons in a position for engagement by one or the other of the pushers 243 and 244.

As each layer of cartons is advanced onto the receiving conveyor 247, such cartons are displaced thereby from right to left, as viewed in FIG. 16, because of the continuous operation of the receiving conveyor. Movement of the cartons along the conveyor is terminated adjacent the forward end thereof by the intermittent stop function performed by the inner edge of the plate 265 (FIG. 18) which is cyclically disposed in and withdrawn from the path of movement of such cartons. Such cyclic movement of the plate 265 is enforced thereon through the cam 263, cam follower 262, and crank arm 261, and whenever the plate is in its lower position of

substantial alignment with the upper reach of the conveyor 247, the forwardmost row of cartons 24 can be advanced from the conveyor onto the plate. The plate is then tipped upwardly to form a stop constraining the successive row of cartons against movement, and the row of cartons then positioned upon the plate 265 is stripped therefrom by the conveyor 267 which displaces such row of cartons onto the color selector infeed conveyor 39.

During such removal of the cartons from the plate 265, they are constrained against movement with the continuously operating conveyor 39 by the alignment plate 274 of the alignment-enforcing mechanism 273, which plate 274 at this time is in a lowered position in which it extends across the conveyor 39. As soon as such row of cartons has been completely displaced from the plate 265 and onto the conveyor 39, the plate 274 is displaced upwardly by action of the cam 286 and cam follower 285 (and associated lever system) to permit the cartons to be advanced by the conveyor 39 to the color selector 38. The stripping conveyor 267 is continuously driven and the plate 265 and alignment plate 274 are movable between the alternate positions thereof in enforced synchronism with the conveyor 267 because they are all driven from the same shaft 252.

Whenever it is desired to by-pass the tote box loader 25 and components of the system following thereafter, the by-pass conveyor 26 is made operative by energizing the motor 179' thereof which drivingly rotates the shaft 139' upon command from the stop mechanism 53, as heretofore explained with respect to the stop mechanism 44, motor 179, and shaft 139 associated with the tote box loader. Whenever the by-pass conveyor 26 is made operative, the motor 179 may be de-energized since there is then no occasion to use the tote box loader 25. The by-pass conveyor 26 in its relation to the infeed conveyor 23 functions in the manner heretofore explained with reference to the tote box loader 25, and in this reference movement of cartons 24 along the infeed conveyor is terminated by abutment of the leading carton in each group thereof with the stop mechanism 53, following which the interrupter mechanism 54 closes to grip the cartons then positioned therebetween, the stop mechanism 53 releases the row of cartons located between it and the interrupter mechanism, and the row-displacing pusher mechanism 55 is made operative to displace such row from the infeed conveyor 23 and onto the by-pass conveyor 26 which carries such cartons to the discharge conveyor 28 for processing in the case packer 29 and palletizer 30, as heretofore explained.

It will be appreciated from all of the foregoing discussion that an article-handling or processing method is comprehended in which articles such as the facial tissue cartons 24 are advanced along a predetermined path defined, in the particular system considered, by the infeed conveyor 23. Such articles are advanced in a substantially continuous procession thereof in which they follow each other in substantially side-by-side juxtaposition. Along such path, the articles are collected into successive groups thereof each comprising a plurality of articles, and the groups are then organized onto successive layers each of which comprises a plurality of groups. Each such layer is formed along the stationary loading platform 48, and it is delivered from such platform to a container for receipt therein, which container in the present instance constitutes a tote box 32.

As explained heretofore, the bottom of the tote box is movable and in the loading of the tote box, the bottom thereof is moved downwardly from an initial position of substantial alignment with the loading platform 48 in step-by-step relation with the successive displacement of layers of articles from such platform so that a receiving surface for each successive layer is always available at a location of substantial alignment with the loading platform. With respect to the first layer received by any par-

ticular tote box 32, such receiving surface constitutes the upper surface of the movable bottom 51 and for each successive layer thereafter, the receiving surface constitutes the upper surface of the preceding layer.

The method of handling articles also comprehends removal thereof from such container which again constitutes a tote box 32 in the particular system under consideration. In unloading such container, the movable bottom thereof is indexed upwardly step-by-step to present and make available each successive layer of articles for removal from the container. After each layer is so removed from the container, it is subdivided into its component groups and the groups are then advanced along a predetermined path for subsequent processing, which path in the apparatus hereof constitutes a color selector infeed conveyor 39. It may be noted that in the event details of the color selector 38 are desired, reference may be made to copending patent application Ser. No. 562,204 filed July 1, 1966, now Pat. No. 3,371,767, dated Mar. 5, 1968; and details concerning the storage bank loader 35 and storage bank 37 can be found in copending patent application Ser. No. 633,137, filed Apr. 24, 1967.

While in the foregoing specification an embodiment of the invention has been set forth in considerable detail for purposes of making a complete disclosure thereof, it will be apparent to those skilled in the art that numerous changes may be made in such details without departing from the spirit and principles of the invention.

What is claimed is:

30. 1. In apparatus for loading into a container therefor a plurality of articles such as facial tissue cartons and the like, an infeed conveyor for advancing such articles in row-like procession, a loading platform adjacent said infeed conveyor for receiving articles therefrom, row-displacing mechanism operative to displace articles in groups thereof from said infeed conveyor and onto said loading platform, layer-displacing mechanism operative to displace from said loading platform and into loading relation with such container a layer of articles comprising a plurality of such groups thereof, conveyor structure for moving a container into loading position with respect to said loading platform so as to receive such articles layer-by-layer therefrom and for subsequently removing loaded containers from such loading position, and mechanism adjacent said loading platform for cooperative action with such container to effect layer-by-layer receipt of such articles therein and including a jack assembly movable between an elevated position adjacent said loading platform and a retracted position therebelow for carrying therebetween a movable bottom provided by such container.

55. 2. The apparatus of claim 1 in which said row-displacing mechanism comprises an elongated pusher extending along said infeed conveyor and transversely of said loading platform and being operative to displace groups of articles transversely from said infeed conveyor and onto said loading platform, and further comprises means for moving such pusher between an outer article-engaging position remote from said loading platform and an inner article-releasing position adjacent said loading platform.

65. 3. The apparatus of claim 2 in which the path of travel traversed by said pusher in moving between the outer and inner positions thereof is transversely across said infeed conveyor, and in which said means for moving said pusher includes mechanism for elevating the pusher to a location above said infeed conveyor sufficient to pass over articles advancing therealong when said pusher moves from said inner to said outer position thereof.

70. 4. The apparatus of claim 1 and further comprising stop mechanism positioned along said infeed conveyor for terminating the advance of articles therealong, and interrupter mechanism disposed along said infeed conveyor a spaced distance from said stop mechanism and being cooperative therewith to define each such successive group of articles therebetween.

5. The apparatus of claim 4 in which said interrupter mechanism comprises carton-gripping structures movable between open and closed positions and being effective in the latter position thereof to grip a carton therebetween and thereby constrain the same against movement along said infeed conveyor, and further comprises means for moving said carton-gripper structures between such open and closed positions thereof.

6. The apparatus of claim 5 in which said stop mechanism includes components operative to withdraw the same from the leading carton in each successive group thereof when said carton-gripper structures are in their closed position.

7. The apparatus of claim 4 in which said interrupter mechanism is selectively operative to permit articles to move therewith and to terminate movement thereof, and in which said stop mechanism includes components operative to withdraw the same from the leading carton in each successive group thereof when said interrupter mechanism is operative to terminate movement of articles.

8. The apparatus of claim 1 and further comprising stop mechanism positioned along said infeed conveyor for terminating the advance of articles therealong, interrupter mechanism disposed along said infeed conveyor a spaced distance from said stop mechanism and coactive therewith to define each such successive group of articles therebetween, and in which said row-displacing mechanism comprises an elongated pusher extending along said infeed conveyor transversely of said loading platform and being operative to displace from said infeed conveyor a group of articles defined between said stop and interrupter mechanisms.

9. The apparatus of claim 8 in which the path of travel traversed by said pusher in moving between the outer and inner positions thereof is transversely across said infeed conveyor, and in which said means for moving said pusher includes mechanism for elevating the same to a location above said infeed conveyor sufficient to pass over articles advancing therealong when said pusher moves from said inner to said outer position thereof.

10. The apparatus of claim 1 in which said layer-displacing mechanism comprises conveyor means operative to displace an entire layer of articles along said loading platform and into loading relation with such container.

11. The apparatus of claim 10 in which said conveyor means includes a pair of spaced-apart conveyor chains and a conveyor flight extending therebetween, said conveyor flight being advanced into pushing engagement with each such layer of cartons to displace the same along said loading platform upon movement of said chains.

12. The apparatus of claim 1 in which said jack assembly comprises a base adapted to support such movable bottom thereon, and further comprises motor means for moving said base downwardly in step-by-step relation with the successive displacement of layers of articles from said loading platform.

13. The apparatus of claim 1 and further comprising presser mechanism adjacent said loading platform at such container-loading position, said presser mechanism being operative to urge articles comprising a layer thereof downwardly toward the interior of such container to positively seat such articles upon a surface underlying the same.

14. The apparatus of claim 13 in which said presser mechanism comprises a plurality of elongated presser feet respectively aligned with groups of articles comprising each such layer thereof.

15. The apparatus of claim 13 and further including a confining displacer extending across the path of movement enforced on each such layer of articles by said layer-displacing mechanism and being operative to enforce on each such layer a limited movement in a direction oppo-

site to the direction of movement imparted to each such layer by said layer-displacing mechanism.

16. In apparatus for loading into a container therefor a plurality of articles such as facial tissue cartons and the like, an infeed conveyor for advancing such articles in row-like procession, a loading platform adjacent said infeed conveyor for receiving articles therefrom, row-displacing mechanism operative to displace articles in groups thereof from said infeed conveyor and onto said loading platform, layer-displacing mechanism operative to displace from said loading platform and into loading relation with such container a layer of articles comprising a plurality of such groups thereof, and conveyor structure for moving a container into loading position with respect to said loading platform so as to receive such articles layer-by-layer therefrom and for subsequently removing loaded containers from such loading position, said row-displacing mechanism comprising an elongated pusher extending along said infeed conveyor and transversely of said loading platform and being operative to displace groups of articles transversely from said infeed conveyor and onto said loading platform, and further comprising means for moving such pusher between an outer article-engaging position remote from said loading platform and an inner article-releasing position adjacent said loading platform, the path of travel traversed by said pusher in moving between the outer and inner positions thereof being transversely across said infeed conveyor, and said means for moving said pusher including mechanism for elevating the pusher to a location above said infeed conveyor sufficient to pass over articles advancing therealong when said pusher moves from said inner to said outer position thereof.

17. In apparatus for loading into a container therefor a plurality of articles such as facial tissue cartons and the like, an infeed conveyor for advancing such articles in row-like procession, a loading platform adjacent said infeed conveyor for receiving articles therefrom, row-displacing mechanism operative to displace articles in groups thereof from said infeed conveyor and onto said loading platform, layer-displacing mechanism operative to displace from said loading platform and into loading relation with such container a layer of articles comprising a plurality of such groups thereof, conveyor structure for moving a container into loading position with respect to said loading platform so as to receive such articles layer-by-layer therefrom and for subsequently removing loaded containers from such loading position, stop mechanism positioned along said infeed conveyor for terminating the advance of articles therealong, and interrupter mechanism disposed along said infeed conveyor a spaced distance from said stop mechanism and being coactive therewith to define each such successive group of articles therebetween, said interrupter mechanism comprising carton-gripping structures movable between open and closed positions and being effective in the latter position thereof to grip a carton therebetween and thereby constrain the same against movement along said infeed conveyor, and further comprising means for moving said carton-gripper structures between such open and closed positions thereof, said stop mechanism including components operative to withdraw the same from the leading carton in each successive group thereof when said carton-gripper structures are in their closed position.

18. In apparatus for loading into a container therefor a plurality of articles such as facial tissue cartons and the like, an infeed conveyor for advancing such articles in rod-like procession, a loading platform adjacent said infeed conveyor for receiving articles therefrom, row-displacing mechanism operative to displace articles in groups thereof from said infeed conveyor and onto said loading platform, layer-displacing mechanism operative to displace from said loading platform and into loading relation with such container a layer of articles comprising a plurality of such groups thereof, conveyor structure for mov-

ing a container into loading position with respect to said loading platform so as to receive such articles layer-by-layer therefrom and for subsequently removing loaded containers from such loading position, stop mechanism positioned along said infeed conveyor for terminating the advance of articles therealong, and interrupter mechanism disposed along said infeed conveyor a spaced distance from said stop mechanism and being coactive therewith to define each such successive group of articles therebetween, said interrupter mechanism being selectively operative to permit articles to move therewith and to terminate movement thereof, and said stop mechanism including components operative to withdraw the same from the leading carton in each successive group thereof when said interrupter mechanism is operative to terminate movement of articles.

19. In apparatus for loading into a container therefor a plurality of articles such as facial tissue cartons and the like, an infeed conveyor for advancing such articles in row-like procession, a loading platform adjacent said infeed conveyor for receiving articles therefrom, row-displacing mechanism operative to displace articles in groups thereof from said infeed conveyor and onto said loading platform, layer-displacing mechanism operative to displace from said loading platform and into loading relation with such container a layer of articles comprising a plurality of such groups thereof, conveyor structure for moving a container into loading position with respect to said loading platform so as to receive such articles layer-by-layer therefrom and for subsequently removing loaded containers from such loading position, said layer-displac-

ing mechanism comprising conveyor means operative to displace an entire layer of articles along said loading platform and into loading relation with such container, and said conveyor means including a pair of spaced-apart conveyor chains and a conveyor flight extending therebetween, said conveyor flight being advanced into pushing engagement with each such layer of cartons to displace the same along said loading platform upon movement of said chains.
